United States Patent Office

Des. 202,314
Patented Sept. 14, 1965

202,314

SOAP BAR

Wesley W. Simpson, New York, N.Y., assignor to Adele Simpson, Inc., New York, N.Y., a corporation of New York

Filed Apr. 9, 1965, Ser. No. 84,696

Term of patent 14 years

(Cl. D73—1)

FIG. 2

FIG. 1

FIG. 3

FIG. 4

FIG. 5

FIG. 1 is a top perspective view of a soap bar showing my new design;

FIG. 2 is a top plan view thereof;

FIG. 3 is a side elevational view thereof, the opposite side being a mirror image;

FIG. 4 is a bottom plan view thereof; and

FIG. 5 is an end elevational view thereof, the opposite end being a mirror image.

I claim:

The ornamental design for a soap bar, as shown and described.
